UNITED STATES PATENT OFFICE.

JOSEPH J. DEUEL, OF BAKERSFIELD, CALIFORNIA, ASSIGNOR TO AXELSON MACHINE CO., OF LOS ANGELES, CALIFORNIA, A FIRM COMPOSED OF CHARLES F. AXELSON AND GUSTAVUS A. AXELSON.

PUMP-PROTECTOR.

1,077,685.

Specification of Letters Patent.

Patented Nov. 4, 1913.

Application filed July 23, 1912. Serial No. 711,170.

To all whom it may concern:

Be it known that I, JOSEPH J. DEUEL, a citizen of the United States, residing at Bakersfield, in the county of Kern and State 5 of California, have invented a new and useful Pump-Protector, of which the following is a specification.

This invention relates to an appliance to be used in connection with deep well pumps, 10 such as the pumps of oil wells and deep water wells which have a working barrel and pump tubing. It is found in practice that the working barrels in which the plungers of said pumps reciprocate are prefer- 15 ably made of cast iron as that material wears smoother and longer; and said working barrels are liable to become broken and in case of breaking much expense and loss of time are incurred in the operation of fishing out 20 broken parts and unless they can be removed they become serious obstructions and in some instances may be driven through the casing by descending tools and may cause the loss of the well.

25 An object of this invention is to provide means easily assembled and applied to the pump whereby breakage of the working barrel is avoided and the serious difficulties referred to are entirely obviated.

30 My invention consists of the combination with a pump tubing, of a working barrel rigidly secured to the lower end of the tubing; an anchor extending downwardly from the working barrel; and a loose connection 35 between the tubing and the anchor; so that if the working barrel breaks in two pieces, the part below the break may be removed from the well by removing the tubing.

The invention may be carried out in vari- 40 ous ways.

The accompanying drawings illustrate the invention.

Figure 1 is a fragmental axial section of the invention applied in one manner to the 45 tubing and working barrel of a deep well pump. Fig. 2 is an enlarged plan cross section on line x^2 , Fig. 1. Fig. 3 is an axial section of the invention as applied with the protecting case and collars loose from the 50 tubing. Fig. 4 is an axial section of the protector as applied with another form of cast-iron working barrel omitting the anchor.

Referring first to the form shown in Fig.

1, the top collar 1 is of steel and provided 55 with internal threads 2 at the top to screw onto the lower end of the pump tubing 3; and is provided at its lower end with the internal threads 4 and the external threads 5. The threaded portions 2 and 4 are pref- 60 erably tapered as in the case of oil well tools, so that the parts joined thereto may be tightly screwed thereon. A steel nipple 6 is screwed into the inner lower threaded portion 4 and is provided at its lower end with 65 a taper-threaded portion 7 to which the working barrel 8 is secured, being in the instance shown fastened thereto by the taper-threaded steel collar 9. The bore of the steel nipple 6 is of greater diameter than 70 the cast-iron working barrel, so that the pump plunger, not shown, will fit the working barrel and not touch the nipple. The nipple 6 and the pump tubing 3 are prefer- 75 ably of practically the same internal diameter. A case 10 preferably formed of a single steel tube is screwed tightly onto the threaded portion 5 and has a screw-threaded portion 11 into which is tightly screwed the internal steel foot collar 12, the inside of 80 the case 10 being thus provided with an annular shoulder 13 below the working barrel 8 that may be connected at its lower end with an anchor pipe 14 which in the instance shown is screwed into a steel collar 15 that 85 is screwed onto the threaded portion 16 at the lower end of the cast-iron working barrel 8. The anchor 14 is common in deep well pumps and no novelty is claimed there- 90 for. The steel collars 9 and 15 are of less external diameter than the bore of the case 10, so that the working barrel is practically 95 free from the case, being suspended from the head collar 1. The bore of the foot collar 12 is of less diameter than the working barrel 8 and its collars 15 and 9 so that there is a clearance between the anchor 14 and the internal foot collar 12, thus to avoid trans- 100 mission of jars from the case to the pump.

In the form shown in Fig. 3 the working 105 barrel 17 is connected to the lower end of the tubing 18 by the nipple 19 and is screwed into the valve seat and thickened collar 20 at the bottom. Outside the tubing 18 and loose thereon is the head collar 21 of less internal diameter than and resting 105 on the collar 19 and having at its lower end a screw-threaded portion 22 onto which

is screwed the steel case 10 to the lower end of which is fixed the steel collar 23 forming an internal annular collar 24 the aperture through which is of less diameter than the 5 external diameter of the working barrel so that the working barrel and its adjuncts cannot escape therethrough in case they become broken.

The form shown in Fig. 4 is much the 10 same as that shown in Fig. 1, the working barrel 17' being cast integral with the collars 25 and 26 and the foot collar 12 and case 10 being rigid with the pump tubing 3. The method of assembling is practically 15 the same as that which will now be described with regard to Fig. 1.

To assemble the appliance shown in Fig. 1 the nipple 6 will be screwed into the threaded seat 4 of the steel collar 1, and the 20 working barrel 8 and its collar 15 will be secured thereto by screwing the several parts together. Then the case 10 will be screwed onto the threaded portion 5 of the head collar and then the foot collar 12 will 25 be screwed into the lower end of the case. If it is desired to use the anchor the same may be connected to the working barrel before the case is screwed onto the head collar.

30 To assemble the form shown in Fig. 3 the collar 21 will first be slipped onto the tubing 18, then the working barrel 17 will be secured by the nipple 19 to the tubing by screwing the parts together and the case 35 10 may be screwed onto the threaded portion 22 either before or after the collar 23 is screwed into said case 10. As with the form shown in Fig. 1 the anchor may be applied or not at the choice of the constructor.

The protector thus constructed and carried by the pump tubing, being applied in combination with the pump tubing and working barrel, protects the cast-iron working barrel from contact with exterior bodies and therefore avoids liability of breakage; and in case any breakage occurs, the internal shoulder of the steel foot collar 12 or 5 the 23 prevents the escape of the pieces from 50 the case. If the working barrel breaks in two, the part below the break may be removed from the well by removing the pump tubing.

The desired service is in good measure 55 effected by the invention as applied in either form, but in the form shown in Figs. 1 and 4 the parts are all securely fixed together while in the form shown in Fig. 3 the case with its shoulder or internal projection 24 60 is loosely connected with the tubing.

I claim:—

1. The combination with pump tubing and a working barrel of means for loosely connecting the pump tubing to the bottom of the working barrel, so that if the working 65 barrel breaks in two, the part below the break may be withdrawn with the pump tubing.

2. A pump protector comprising, a case adapted for inclosing the working barrel of 70 a pump; means for connecting the case to the lower end of the pump tubing; and means for loosely connecting the lower end of the case to the lower end of the working barrel, so that if the working barrel breaks 75 in two, the part below the break may be removed by removing the tubing.

3. The combination with a pump tubing, of a working barrel rigidly secured to the lower end of the tubing; an anchor extending 80 downwardly from the working barrel; a case adapted to inclose the working barrel; said case being longer than the working barrel; a connection between the upper end of the case and the pump tubing; and 85 a loose connection between the lower end of the case and the lower end of the working barrel; so that if the working barrel breaks in two, the part below the break may be withdrawn by withdrawing the pump tub- 90 ing.

4. In a pump the combination with the tubing and working barrel, of a collar fixed to the tubing and of greater diameter than the tubing, a collar of greater diameter than 95 the tubing loosely mounted on the tubing above and resting on the first-named collar, a case fastened to the loose collar and inclosing the working barrel and provided with an internal projection below the working barrel to prevent escape thereof. 100

5. A pump protector comprising, the combination with a tubing and working barrel of a case longer than the working barrel and adapted to inclose the working 105 barrel; a loose connection between the upper end of the case and the lower end of the tubing; and a loose connection between the lower end of the case and the lower end of the working barrel; so that if the working 110 barrel breaks, it cannot get out of the case.

In testimony whereof, I have hereunto set my hand at Bakersfield, California, this 16th day of July, 1912.

JOSEPH J. DEUEL.
